GAME OF SKILL

Karges Lauterbach, Irondequoit, N. Y.

Application October 17, 1936, Serial No. 106,179

28 Claims. (Cl. 273—86)

This invention relates to games, and more particularly to games of skill.

An object of the invention is to provide an improved game which will hold the interest and attention of the players.

Another object is the provision of such a game in a form which is relatively easy and inexpensive to manufacture and easy to maintain in proper working order.

Still another object is the provision of a game of skill so arranged as to indicate automatically the winner or winners of the game.

A further object is the provision of a game so constructed as to indicate rewards to be delivered to the winner or winners.

A still further object is the provision of improved means for automatically paying rewards in different amounts to the various winners.

Still another object is the provision of means dependent upon the number of persons playing the game for varying the amount and number of the rewards.

A still further object is the provision of reward indicating mechanism which is substantially fool-proof and not susceptible of tampering.

Another object is the provision of a game of the type in which two or more playing pieces are moved along tracks, in combination with impedance means for interrupting the smooth movement of the playing pieces along the tracks.

To these and other ends the invention resides in certain improvements and combinations of parts, all as will be hereinafter more fully described, the novel features being pointed out in the claims at the end of the specification.

In the drawings:

Fig. 1 is a plan of game apparatus constructed in accordance with a preferred embodiment of the invention;

Fig. 2 is an elevation of certain parts of the operating mechanism of the apparatus, with parts in vertical section and with parts removed for the sake of clearness;

Fig. 3 is a side view of one of the movable playing pieces attached to the flexible element which moves it;

Fig. 4 is a view of such a playing piece in one position with respect to the impedance means associated therewith;

Fig. 5 is a similar view of the playing piece in a different position with respect to such impedance means;

Fig. 6 is a plan of a fragment of the apparatus showing the construction of a part of the impedance means;

Fig. 7 is a plan of part of the apparatus on a larger scale than Fig. 1, showing additional details, with part of the controlling mechanism in one position;

Fig. 8 is a similar view with part of the controlling mechanism in a different position;

Fig. 9 is a vertical section taken transversely across the tracks just in advance of the control barrier;

Fig. 10 is a view similar to a fragment of Fig. 10 9, showing certain of the parts in a different position;

Fig. 11 is a vertical section taken longitudinally along one of the tracks, with a playing piece just in advance of the control barrier;

Fig. 12 is a similar view with the playing piece in a different position;

Fig. 13 is a similar view with the playing piece in still another position;

Fig. 14 is a vertical section taken transversely across one of the tracks, illustrating details of one of the electrical switches associated therewith;

Fig. 15 is a horizontal section through one of such electrical switches, with the switch in open position;

Fig. 16 is a similar view with the switch in closed position;

Fig. 17 is an elevation of another electrical switch;

Fig. 18 is a horizontal section through the switch shown in Fig. 17, with the contacts in open position;

Fig. 19 is a side elevation of certain of the electrical parts for determining the winner or winners of the game;

Fig. 20 is a plan of the parts shown in Fig. 19, with parts removed for the sake of clearness;

Fig. 21 is an enlarged view of one of the winner selecting assemblies shown in Figs. 19 and 20, with the parts in a different position;

Fig. 22 is a plan of the parts shown in Fig. 21, in the position there indicated;

Fig. 23 is an end view of the parts shown in Figs. 21 and 22;

Fig. 24 is an elevation, with parts in vertical section, of certain timing mechanism constituting a part of the apparatus, shown in one position;

Fig. 25 is a similar view of the parts in a different position;

Fig. 26 is a plan of the timing parts, illustrated in Fig. 24, showing them in the same position there illustrated;

parts in the different position indicated in Fig. 25;

Fig. 28 is a fragmentary view illustrating the cooperation with certain parts of the timing mechanism;

Fig. 29 is a plan of part of the timing mechanism with the parts in one position;

Fig. 30 is a similar view with the parts in a different position;

10 Fig. 31 is a wiring diagram illustrating the circuit controlling means for disconnecting an operating crank from its associated playing piece, with the parts in one position;

15 Fig. 32 is a similar view with the parts in different position;

Fig. 33 is an elevation, with parts in vertical section, of part of the mechanism for delivering rewards or prizes to the winner or winners;

20 Fig. 34 is a vertical section on a larger scale of part of the reward delivering mechanism;

Fig. 35 is a fragmentary vertical section of certain of the parts illustrated in Fig. 34, viewed from a different direction, and

25 Fig. 36 is a wiring diagram showing the principal electrical circuits of the mechanism for selecting and indicating the winner or winners and for delivering the rewards or prizes.

The same reference numerals throughout the several views indicate the same parts.

30 Apparatus constructed in accordance with a preferred embodiment of the invention will now be described, with reference to the accompanying drawings, but it is to be understood that the apparatus is capable of many variations and modifications without departing from the invention, and that many features of the invention may be used without other features, so that the apparatus now to be described is to be regarded only as an illustrative example, and not as a limitation upon the invention.

35 The illustrative apparatus comprises a case or cabinet suitably supported, having a glass top 40, and a playing board surface 41, of metal, wood, or other suitable material, arranged approximately horizontally below the glass 40. In the playing board 41 are any desired number of tracks, six being here shown, these tracks being indicated by the numerals 51 to 56, respectively. Suitable playing pieces, such as representations 40 of dogs, horses, or other running animals, are arranged to move around these six tracks. When representations of dogs are used, there is preferably a seventh track 57 inside the six dog tracks, and a representation of a rabbit 101 arranged 45 to move around this seventh track, in order to make the game a more realistic simulation of an actual dog race track as currently used for racing greyhounds.

50 Each of the tracks 51 to 56 may be formed by a slot extending through the board 41, with a channel 45 (Fig. 9) beneath each slot. Each channel forms a guideway for a chain 46 extending continuously around the track, each chain having at one point an upstanding member 47 secured thereto. The post 47 extends upwardly from the chain through the slot in the board 41 and projects to a substantial height above the top 55 of the board. Each post 47 has pivoted to it a representation of the desired animal, such as the greyhound 48, mounted on the horizontal pivot 49 (Fig. 11) and having a cavity 50 in its body into which the upper end of the post 47 extends. The pivot 49 is placed slightly forwardly of the center of gravity of the animal, so that the rear 60 end of the animal tends to tilt downwardly by

gravity. But the cavity 50 is so formed around the upper end of the post 47, that the walls of the cavity contact with the post and prevent the rear end of the animal from tilting downwardly below the normal position shown in Figs. 3, 4, 5 11, and 12, although the rear end can rise and the front end can move downwardly to a substantial extent from this position, as shown, for example in Fig. 5.

Each chain 46 of each dog track 51 to 56, inclusive, is independently driven by means under the control of a person playing the game. Each driving means may comprise, for example, a chank 61 in an accessible position (Figs. 1 and 9) driving a shaft 62 extending into the casing 10 and having on its inner end a sleeve 63 longitudinally slidably on the shaft but non-rotatably connected thereto, so as to rotate with the shaft. The sleeve 63 constitutes part of a disengageable clutch and has on its inner annular 15 end a notch 64 for engaging a radial pin 65 on a shaft 66 which is arranged coaxially with the shaft 62. A spring 67 constantly tends to move the sleeve 63 outwardly toward the crank 61 and thus to disengage the connection between the shafts 62 and 66. A member 70 surrounding the shaft 62 may be moved leftwardly when viewed as in Fig. 9, however, by suitable mechanism to be described below, in order to move the clutch sleeve 63 leftwardly and thus engage the clutch 20 as shown in Fig. 10. A spring 71 is interposed between the member 70 and clutch sleeve 63 so that if the member 70 should be moved leftwardly at a time when the notch 64 is not correctly aligned with the pin 65, no breakage of 25 the parts would occur but the clutch would become properly engaged as soon as rotation of the shaft 62 brings the notch 64 into alinement with the pin 65. When the member 70 is moved leftwardly to engage the clutch, it is held in clutch- 30 engaging position by a latch 73 which is maintained in latching position by a spring 74 and which holds the clutch in engaged position until the latch 73 is withdrawn by energizing an electro-magnet 75, which pulls the latch 73 downwardly from the position shown in Fig. 10 to the 35 position shown in Fig. 9 and allows the spring 67 to disengage the clutch.

40 When the clutch is engaged, rotation of the shaft 63 by the crank 61 will cause corresponding rotation of the shaft 66, driving a beveled gear 77 meshing with another beveled gear 78 on a vertical shaft 79 which carries a disk 80 having a non-rotatable connection with the shaft 79 but free to move vertically thereon. This shaft 79 is controlled by centrifugal governor mechanism indicated in general at 82 (Fig. 2) so that as the speed of rotation of the shaft 79 increases, the governor mechanism causes the disk 80 to move up the shaft, and when the shaft 55 80 is stationary, the disk 80 is at its lowermost position, as indicated in Fig. 2.

50 The periphery of the disk 80 engages with the face of another disk 85 which is non-rotatably secured to a horizontal shaft 86 and capable of slight longitudinal movement thereon, and is constantly pressed into engagement with the disk 80 by a spring 87 which is interposed between the disk 85 and a nut 87a. By adjusting the nut, the tension on the spring can be varied. The 60 shaft 86 carries a bevel gear 88 meshing with another bevel gear 89 on a vertical shaft 90 which has at its upper end a sprocket 91 meshing with the track chain 46. The above described driving mechanism is duplicated for each track, and all 75

of the driving mechanisms may be the same except the drive for one of the tracks, which is so arranged that this driving mechanism also drives the rabbit running around the track 57.

6 This special drive for the rabbit is indicated in Fig. 9, where the shaft 66 is extended beyond the beveled gear 77, whereas in the other drives the shaft is cut off just beyond the gear 77. The extended shaft 66 carries another beveled gear 95 meshing with a gear 96 on a vertical shaft 97 which has at its upper end a sprocket 98 meshing with a chain 99 in the rabbit track 57, which rabbit track may be formed by a channel-shaped member turned on its side as shown in Fig. 9. 10 The rabbit chain 99 has a laterally extending post 100 which extends out through the continuously open side of the channel and which carries the representation of the rabbit 101.

15 In the form here shown, it is the drive for the dog track 51 which also drives the rabbit 101, although the rabbit could obviously be driven from the drive of any desired one of the dog tracks. All of the drives for the dog tracks 52 to 56, inclusive, may be identically constructed, 20 and the different distances of the respective tracks from the edges of the casing where the cranks 61 are mounted, may easily be taken care of by placing the shafts 86 in different annular relations to the shafts 62 and 66, as indicated 25 diagrammatically in Fig. 1.

30 When any one of the cranks 61 is turned slowly (the clutch 63-65 being engaged) the disk 80 will be near the periphery of the disk 85 and will drive the chain 46 of the associated dog track 35 with the maximum power ratio but at relatively slow speed. As the speed of rotation of the crank 61 is increased, the speed of travel of the chain 46 increases even more rapidly, because in addition to the faster rotation of the crank, the driving ratio is also changed by the centrifugal 40 governor 82 lifting the disk 80 up to a point closer to the center of the disk 85. As the crank 61 is turned still more rapidly, however, the disk 80 is lifted to a point at or so close to the axis 45 of rotation of the disk 85 that there is insufficient power to overcome the friction of the chain 46 and associated parts. Hence the driving of the chain stops, and the person turning the crank 61 must stop the rotation of the crank or slow 50 it down to a great extent, until the driving relationship is again established. This irregularity as to the maintenance of the driving relation makes the game more interesting and makes it truly a game of skill rather than a game of chance, because it requires skill on the part of 55 the operator, acquired by tests and experience, to determine at just what rate he should turn his crank 61 in order to drive his chain 46 to get his dog 48 around the track in the minimum 60 time.

Those tracks which are closer to the center of the board will, of course, be slightly shorter than the outermost tracks. This difference in length of tracks can be compensated for in various ways, such as by using driving sprockets 91 of slightly different sizes for the different tracks, or by slightly changing the gearing 88-89 or the gearing 77-78, or the diameter of the disk 80, in the drives in the different tracks, so that 65 the player of each track has an equal chance and the shorter tracks are not given preference over the longer tracks.

In order to make the game still more interesting, it is desirable to have impediment means or 70 obstruction means associated with the tracks, so

that the dogs cannot move smoothly or continuously around the tracks except at a certain speed within narrow limits. Indeed, the impediment means may be so constructed that the dogs cannot move continuously at any speed, but in 5 all cases may have to stop and then start again.

10 The impediment means may be constructed as shown in Figs. 1, 4, 5, and 6. On both sides of each track, in position to be struck by the hind legs of the dog moving along that track, 15 is a ramp 120, constituting part of what may be described as hurdle means, and a little in advance of each ramp 120 is placed, on both sides of the track slot, an upwardly projecting member 121, constituting another part of the hurdle 20 means. In order to make the position of the member 121 with respect to the member 120 somewhat adjustable, the upstanding member 121 is preferably formed as part of a flat bar 122 having a downwardly projecting tongue 123 25 which may be placed in any one of a series of slots 124 in the board 41. A screw 125 extending through a slot in the bar 122, holds it down in proper position.

30 As the dog passes along the track, his hind legs strike the ramp portion 120 of the hurdle which causes the rear end of the dog to tilt upwardly, depressing the front legs until they are below the level of the top of the member 121 of the hurdle. If the dog is traveling fast, the 35 front legs will be caught by the member 121 and further progress of the dog will be arrested, as indicated in Fig. 5, stopping the movement of the chain and causing the disk 80 to slip on the disk 85. The person turning the crank connected 40 to this dog must then stop turning the crank forwardly and turn the crank rearwardly a slight amount, until the front legs of the dog are withdrawn from beneath the somewhat overhanging hurdle member 121, and wait until gravity has a 45 chance to tilt the rear end of the dog down to its normal position, raising the front feet above the top of the member 121. Forward turning of the crank may then be resumed to drive the dog further around the track. If the dog is moving 50 somewhat slower, however, then after the rear legs pass off of the ramp 120, gravity will have a chance to restore the dog to normal position before the front legs reach the member 121, and thus the hurdle means will not interrupt the 55 travel of the dogs. Whether or not the dog is arrested by the hurdle means will thus depend upon the speed at which the dog is traveling and the distance between the members 120 and 121 of the hurdle means. By placing a number of 60 hurdle means at different points around the track, preferably at least at three or four different points on each track, and by adjusting the spacing of each hurdle means on each track somewhat different than the spacing of the 65 others, the playing of the game is rendered more difficult and interesting.

In Fig. 1, only two hurdle means on each track are indicated, the others being omitted for the sake of clearness, and it will be observed that the 70 spacing of the second hurdle means on each track is different from the spacing of the first hurdle means. Thus it takes considerable skill and experience for the player to run his dog over all of the hurdle means without interruption of the 75 travel of the dog, and yet at a sufficiently fast pace to stand a reasonable chance of winning the race.

In order that there may be some revenue to the proprietor of the game, suitable coin controlled 75

mechanism of any conventional construction is combined with the other parts of the apparatus. Preferably, but not necessarily, there is a separate coin controlled mechanism for each separate crank 61 operating the dog on one track. Thus any number of dogs may be run in playing the game, but a coin must be inserted in the corresponding coin controlled mechanism in order to permit operation of each individual dog.

Each coin controlled mechanism may include a slide member 130 (Figs. 1, 7, and 8) having therein an opening 131 for receiving a coin. When a coin is placed in this opening and when the slide 130 is shoved inwardly from the position shown in Figs. 1 and 7 to the position shown in Fig. 8, the inward movement of the slide causes an inward swinging of the bar 70 (Figs. 7, 9, and 10) to close the clutch 64, 65 and effect a driving connection between the crank 61 and the shaft 63 of the particular track associated with the coin controlled mechanism which was thus operated. The clutch is held closed by the latch member 73, as above explained, until the dog has completed its course around the track. At or approximately at the time that the dog reaches the finish line of the race track, it closes an electric switch member 136 (Figs. 31 and 32) to complete a circuit through contact members 137, which circuit includes a battery or other suitable source of current 138 and suitable leads or wires 139 and 149 connecting the battery and the contacts 137 to the magnet 75. When the switch 136 is moved from the open position of Fig. 31 to the closed position of Fig. 32, at the time the dog reaches the finish line or shortly thereafter, the electro-magnet 75 is energized, the latch 73 is drawn down from the position of Fig. 31 to the position of Fig. 32, and this releases the member 70, permitting the spring 67 to open the clutch 64, 65 and to break the driving connection between the crank 61 and the dog. Further turning of the crank 61 is ineffective, and the dog cannot be run further around the track unless and until another coin is inserted in the coin controlled mechanism which controls this particular dog, to move the clutch 64, 65 once more to its closed position.

The coin controlled mechanism is shown only diagrammatically in the present drawings, since the details thereof may be constructed in any known manner. It is to be understood that in this diagrammatic showing, the slide 130 cannot be shoved inwardly until the proper coin has been placed in the receiving opening 131, or, if the mechanism is of the type in which the slide can be moved in the absence of a coin, then the outer accessible part of the slide is connected to an inner non-accessible moving part only when the coin is inserted, and this inner part of the slide 60 is the one which moves the member 70.

The rabbit 101 is moved around its track by any desired one of the cranks 61 associated with any desired one of the tracks. In the present illustrative embodiment, it is the crank 61 operating upon the outermost track 51 which controls the movements of the rabbit 101. Since it is desired to make the rabbit run in all races, no matter how many dogs are running, means are provided for controlling all of the dogs from the coin controlled mechanism of the track 51, so that no other dogs can run unless a coin has been deposited in the coin controlled mechanism controlling the track 51. Except for the necessity of depositing a coin always in the mechanism for track 51, there are no other restrictions as to any

particular dogs or any number of dogs which may be run, and the dog of the track 51 may be run by itself, or with any other one or more dogs of any other tracks.

The control mechanism requiring insertion of a coin in the coin slot of track 51, may include a barrier bar 150 (Figs. 7, 8, 9, and 11) extending transversely across all of the tracks and having upwardly looped portions 151 normally out of alignment with the track slots but spaced at the same intervals as the lateral distances between the track slots. The portions of the bar 150 between the loops 151 lie substantially flat on the board 41, as best shown in Fig. 9. They carry strong fingers 153 projecting in a direction along the track slots, as best shown in Fig. 7. The fingers 153 are normally aligned with the track slots and act as stops to contact with the supporting posts 47 of the several dogs to stop the movement of these dogs just after they pass the finish line. In Fig. 11, one of the dogs is shown in a position just past the finish line, with its post 47 against the end of the finger 153, which prevents further movement.

When a coin is inserted in the coin controlled mechanism associated with the track 51 and when the slide 130 is shoved inwardly, a pin 160 on the slide contacts with an arm 161 connected to the bar 150 and moves this bar longitudinally (or in a transverse direction with respect to the tracks) against the force of a light spring 162, until the fingers 153 are shifted out of alignment with the track slots to the position shown in Fig. 8, and the upwardly extending loops 151 are brought into alignment with the track slots. Any players who have meanwhile deposited the required coins may then turn their cranks to move their respective dogs past the barrier 150, through the loops or arches 151. The player who plays track 51 meanwhile keeps his coin 40 slide 130 shoved inwardly until he has moved his own dog past the barrier and until all of the other players who intend to participate in this race have done likewise. When all of the dogs which are to be run in this race have passed the barrier, the player operating track 51 releases the coin slide, and the spring 162 restores the barrier 150 to its normal position shown in Fig. 7.

The clutch operating member 70 for track 51 may conveniently be actuated by a pin 165 depending from the barrier 150, as shown in Figs. 7 and 9. The corresponding clutch operating members 70 for the cranks of the other tracks can be operated directly from the coin slides or other suitable parts of the coin controlled mechanism controlling the respective tracks.

After the respective dogs have passed the barrier 150, their cranks 61 may be turned to move the dogs up into a kennel 180 (Figs. 1, 7, and 12) until the front legs of the dog come into contact with the front door 181 of the kennel, which is pivoted about a hinge 182 at its upper edge. A single door 181 may extend across the full width of all of the tracks. The kennel door is held closed by a latch 183 (Figs. 9 and 12) which projects upwardly to overlap the lower edge of the door, and which is pivoted to a control bar 184 mounted on a fulcrum 185 and urged upwardly by a light spring 186. The players turn their cranks slowly, the front legs of the respective dogs meanwhile pushing against the door 181, and the disks 80 slipping upon the disks 85. The player who is playing track 51 continues rotating his crank until the rabbit 101 is brought around to a point adjacent the kennel 75

180. It will be noted that the drive of the rabbit is from the same crank which controls the dog track 51, but the rabbit drive does not go through the friction disks 80 and 85. Thus, when the 5 dog running on track 51 is in the kennel and held stationary by the door 181 of the kennel, the crank 61 of the track 51 may nevertheless be rotated to move the rabbit, and the slipping of the disk 80 on the disk 85 will not interfere with 10 the drive of the rabbit.

As the rabbit passes the kennel, a cam member 190 (Figs. 9 and 13) secured to the rabbit contacts with the inclined upper end 191 (Figs. 7, 8, and 9) of a link 192 pivoted to the control 15 bar 184. This pushes the lever 192 downwardly to move the control bar 184 downwardly about its fulcrum 185, and pulling downwardly on the latch 183 to release the kennel door 181. The pressure of the dogs pressing forwardly on the 20 rear side of the door immediately opens the door as soon as the latch 183 is released, the dogs pass forward, swinging the door upwardly and forwardly as they go, and the race is on (Fig. 13).

The respective players operate their cranks in 25 the manner which, in their judgment and according to their skill, will bring their dogs around the track in the least possible time, and cause the least possible interruption in jumping the hurdles 120, 121. The winner is, of course, the 30 one who first brings his dog around to the finish line. This finish line is just in advance of the free ends of the stop members or fingers 153, or left hand ends of these fingers as viewed in Figs. 7 and 11. The finish line may be indicated by 35 a visible mark or stripe extending across the tracks, and arrival at the finish line may also be indicated by electric means or other suitable indicating or registering means, if desired.

The mechanism thus far described provides an 40 interesting game of skill, closely simulating, on a miniature scale, an actual greyhound race as run with live dogs.

The dogs all start off simultaneously when the kennel door is opened, and just as the rabbit 45 is passing the kennel, thus producing a very realistic effect. The rabbit may, and preferably is, geared to run somewhat faster than the dogs, so that even if the player operating the crank of track 51, be relatively slow and unskilful, the 50 rabbit will nevertheless usually stay ahead of the fastest dog. In fact, the rabbit driving mechanism may be geared, if desired, to run the rabbit two or more times around the track during a single circuit made by the dogs.

55 While the foregoing described mechanism provides an interesting and highly entertaining game, yet it is frequently desirable to add further mechanism to the game, for the purpose of distributing prizes, tokens, or rewards to one or more winners. An embodiment of this additional mechanism will now be described.

In its preferred form, the prize, token, or reward distributing mechanism includes means for varying the number and amount of the tokens 60 or rewards in accordance with the number of dogs which run in the race, or partly in accordance with the number of dogs which are conditioned or set to run in the race by insertion of a coin in their respective coin controlled mechanisms, whether or not they actually run.

The prize or reward mechanism includes a series of switches associated with each track for operation by the dogs as they move along the track. In connection with each track these 75 switches may be mounted on four switch bars,

those of the track 51 being designated as 211, 221, 231, and 241, those of track 52 being designated as 212, 222, 232, and 242, and so on, the switch bars of the inside track 56, shown in Figs. 11 to 13, inclusive, being designated as 216, 5 226, 236, and 246, respectively.

Each of these switch bars may be of similar construction, except that some of them may carry more electrical contacts than others. One of the switch bars, such as the switch bar 216, 10 is shown in detail in Figs. 14 to 16. It comprises a block of insulating material mounted to swing about a pivot 260 near its upper end, the ends of the pivot extending into the side plates 261 of an inverted channel-shaped member on which 15 the switch parts are conveniently mounted. A spring 262 (Fig. 13) constantly tends to swing the switch bar in one direction, but such swinging is resisted by a latch including a vertical shaft 263 mounted to rotate about its axis, the 20 lower end of the shaft extending horizontally at 264 along the side of the switch bar 216 and then being bent to extend laterally as at 265 to overlie an edge of the switch bar. A leaf spring 266 tends to hold the latch part 265 in latching relation to the switch bar. The upper end of the shaft 263 has an arm 268 extending laterally across the path of travel of the dog running on the track associated with this particular switch mechanism. As the post 41 on which this dog is 25 mounted moves along the track, it contacts with the arm 268 as indicated in Fig. 14, and thus moves this arm and swings the shaft 263 from the position shown in Fig. 15 to the position shown in Fig. 16, withdrawing the latch 265 to 30 the ineffective position shown in Fig. 16 and permitting the spring 262 to swing the switch bar 216 to the left when viewed as in Fig. 13.

The switch bar 216 may be made of suitable insulating material, such as wood or a molded 40 composition, and may carry one or more metallic contact parts, one of which is indicated by the numeral 270. When the switch is open, the metallic piece 270 is spaced from the contact members 271, but when the latch is released and 45 the switch is closed by its spring, the metal piece 270 makes a contact with both of the spaced members 271 and thus completes the circuit at this point. The number of contact members 270 on the respective switch bars 211 to 246, inclusive, varies according to the number of circuits which need to be closed when that particular switch bar is moved, and each contact member 270 cooperates with its own individual pair of 50 circuit members 271. Except for this variation 55 in the number of contacts on each switch bar, however, mechanical construction of all of the switch bars 211 to 246, inclusive, may be the same.

The switch bars 211 to 216, inclusive may be 60 described as the finish line switches, and the trip members 268 for controlling these switches are at the finish line, which is just in advance of the left hand ends of the fingers 153. In Fig. 65 11, the dog has just tripped the finish line switch of his track and allowed this switch to be closed by its spring, and the dog has come to rest against the end of the stop finger 153 associated with his track. The previously mentioned switches 136, 137 (Figs. 31 and 32) which disconnect the driving cranks from the dogs, are mounted on these switch bars 211 to 216, inclusive, so that as each dog reaches the finish line, his associated clutch will be disconnected and the 70 crank controlling this dog will remain ineffective 75

until another coin is properly inserted in the coin controlled mechanism associated with this particular dog track.

The other three switch bars of each dog track, such as the bars 226, 236, and 246 of track 56, may all be mounted together in a single inverted channel-shaped member 261, as seen in Fig. 13, for ease of assembly. Similarly, the switch bars 225, 235, and 245 of track 55 are mounted together in one inverted channel, and so on for the other tracks. The last two switch bars (which would be numbered 231 and 241) of the main or control track 51 are not needed, however, and may be omitted, because the dog on track 51 is always supposed to run in all races, no matter how many other dogs run, and accordingly it is not necessary to have this dog close certain switches which the other dogs must close in order to determine the number of dogs running in the race and the number and amounts of the prizes or rewards to be distributed.

The electrical relationship of the various switches mounted on the switch bars 211 to 246, inclusive, and their functions and correlations with each other, can best be described with relation to the wiring diagram, Fig. 36, but before proceeding to this description it will be convenient to describe the mechanical construction of certain other switch bars included in the electric circuits, so that such mechanical construction may be understood before the circuits are traced.

Referring now to Figs. 13, 17 and 18, there are two switch bars 301 and 302 mounted to swing on the pivots 303 and 304 near their upper ends, which pivots are mounted in an inverted channel 305. The switch bars 301 and 302 are relatively wide, and are not associated with any one individual dog track but relate collectively to all of the tracks. Springs 307 and 308, respectively, tend to swing these switch bars about their pivots to move their lower ends leftwardly when viewed as in Fig. 13. Such leftward movement is resisted by latches 311 and 312, respectively, which are mounted on armatures in electro-magnets or solenoids 313 and 314, respectively. When either of the solenoids or magnets 313 and 314 is energized, its corresponding latch 311 or 312 is withdrawn to an ineffective position, and the spring 307 or 308 then swings the switch bar 301 or 302, as the case may be, leftwardly from the position shown in Fig. 13. Such leftward swinging of the bar 301 is indicated in Fig. 11.

Both of these switch bars 301 and 302 may be formed of insulating material as in the case of the bars 211 to 246, inclusive, and each of them may carry a considerable number of contact members for cooperation with fixed circuit or contact members when the switch bar is in one or the other of its two positions. Both of the switch bars are arranged to close certain contacts when the bars are in their initial or unreleased positions shown in Fig. 13, and to open these contacts and close other contacts when the bars are swung by the springs 307 and 308 from these initial positions to the other or released positions. The various circuits closed and opened by movements of these switch bars will be described in connection with Fig. 36.

These switch bars 301 and 302 are actuated in accordance with the number of dogs running each race, and the actuation of these switch bars determines the number and amount of

prizes or rewards to be distributed to the winner or winners. The number and amounts of prizes may be varied according to choice, but in the present illustrative embodiment including six dog tracks, it may be assumed that when all six dogs run the race, prizes of varying amounts are to be distributed to the players who play the dogs making first, second, and third place in the race; that when three, four, or five dogs run in the race, a prize is to be given to the player playing the dog who makes first place, but no prize to the players of the second and third place dogs, and the prize to the first place dog being of different amount from the prize given to the player of the first place dog when all six dogs run; and that when only one or two dogs run in the race, no prizes are to be paid to any dogs.

Thus, in this illustrative embodiment, there are three general conditions as to number and amounts of prizes, irrespective of which particular dogs make first, second, or third place. First, there is the condition when all six dogs run, and when three prizes are to be distributed. This condition may be controlled, for example, by actuation of the switch bar 301, without actuation of the bar 302. Next, there is the condition when three to five dogs run, and when a single prize is to be distributed to the winner. This prize distribution may be controlled by actuation of the switch bar 302, without actuation of the bar 301. Last, there is the condition when less than three dogs run, and when no prize is to be distributed to the player of any dog. This lack of prize distribution may be effected by not actuating either of the switch bars 301 and 302 when less than three dogs run.

Referring now to the wiring diagram in Fig. 36, the circuits for actuating the switch bars 301 and 302 in accordance with the number of dogs running the race will now be described. In Fig. 36, the showing is, of course, entirely schematic or diagrammatic, no attempt being made in this diagram to show actual structure, but only to show the circuits and the functions which they perform. The switch bar 301, its latch 311, and its controlling solenoid or electro-magnet 313 are shown near the left hand edge of the wiring diagram. The other switch bar 302, its latch 312, and its controlling solenoid or electro-magnet 314, are shown near the center of the diagram.

A suitable source of current, such as a battery, is indicated at 319. From one side of this battery, a wire 320 extends to electrical switches 322, 323, 324, 325, and 326, mounted on the switch bars 222 to 226, respectively, of tracks 52 to 56, respectively. No corresponding switch is needed on track 51, because the dog running on track 51 is always supposed to run in all races. In any event, the game cannot be operated and no race can be run unless the coin controlled mechanism for the track 51 has been operated, and if the proper coin has been inserted in this mechanism, it is immaterial to the proprietor of the game whether the dog of this track actually runs the race or not, so long as the fee has been paid.

The circuit from the battery after passing through all of the six switches 322 to 326, inclusive, in series, next passes in series through corresponding switches 332 to 336, inclusive, mounted on the switch bars 222 to 226, inclusive, of tracks 52 to 56, respectively. Then the circuit goes to the electro-magnet or solenoid 313. From there it passes through a switch 349 mounted on

the switch bar 381, this switch being normally closed when the switch bar has not been actuated and being open when the switch bar has been actuated; thence through a similar switch 341 on the switch bar 302, which switch is closed when the switch bar 302 has not been actuated and open when the switch bar has been actuated; thence back to the opposite side of the battery 319.

When all six dogs run the race (or if the dogs on tracks 52 to 56 all run the race, the fee for dog 51 having been paid but this dog not actually running) it is apparent that as the dogs pass the trip controlling the second set of individual track switch bars 222 to 226, inclusive, the dogs will trip these switch bars and close the switches 332 to 336. A little further on, the dogs will trip the switch bars 232 to 236 of the third set of individual track switch bars, and will close the switches 322 to 326, inclusive. Since neither of the switch bars 301 and 302 has yet been actuated both of the switches 340 and 341 will be closed. Thus, the circuit to the solenoid or magnet 313 will be completed, the latch 311 will be withdrawn, and the switch bar 301 will be moved by its spring 307. The actuation of this switch bar will immediately open the switch 340, to open the circuit and thus prevent waste of electric current by thereafter continuing the energization of the solenoid or magnet 313. Moreover, the opening of the switch 340 prevents the switch bar 302 from being actuated.

If less than all of the dogs on tracks 52 to 56, inclusive, should run in the race, then one or another of the switches 322 to 326 and the corresponding one of the switches 332 to 336 will not be closed, the circuit to the solenoid or magnet 313 will not be closed, and the switch bar 301 will not be actuated. If any two or more dogs on tracks 52 to 56 do run, however, the circuit will be closed to magnet or solenoid 314 and the switch bar 302 will be actuated, provided switch bar 301 has not previously been actuated.

This is done by means of the switches and circuits now to be described.

On the third set of switch bars 232 to 236 are switches 352 to 356, respectively, which may be conveniently referred to as the "350" group of switches. On the switch bars 233 to 236 are also mounted the switches 363 to 366, respectively, which may be referred to as the "360" group of switches. On the switch bars 234 to 236 are mounted switches 374 to 376, respectively, which may be referred to as the "370" group of switches. On the switch bars 235 and 236 are also mounted switches 385 and 386, respectively, which may be called the "380" group of switches.

On the fourth or last group of individual track switch bars 242 to 246 are switches 392 to 396, respectively, which may be called the "390" group of switches. Also on the switch bars 243 to 246 are the switches 403 to 406, respectively, called the "400" group of switches. On the switch bars 244 to 246 are the switches 414 to 416, respectively, called the "410" group of switches. And on the switch bars 245 and 246 are the switches 425 and 426, respectively, which may be referred to as the "420" group of switches.

The switches of the groups 350 to 420, inclusive, are arranged, as will be apparent from Fig. 36, in the circuit leading from the battery or source of current 319 through the switches, and then to the solenoid or magnet 314, then through the switches 340 and 341, and then back to the op-

posite side of the battery or source of current 319. It will also be apparent from inspection of Fig. 36 that if the switches of the groups 350 to 380 are closed on any two or more dog tracks, by two or more dogs operating the trips of their respective switch bars of the third or 230 group of switch bars, and if the corresponding track switches are closed in the groups 390 to 420, by actuation of the respective switch bars of the fourth or 240 group of switch bars, then the circuit will be completed through the solenoid or magnet 314, provided only that the switches 340 and 341 are closed. It does not matter which two dogs run on the tracks 52 to 56, inclusive, so long as two or more dogs move past the third or 230 group and the fourth or 240 group of switch bars. If all five dogs on the tracks 52 to 56 are running, they will previously have actuated the switch bars of the second or 220 group and of the third or 230 group, before they arrive at the fourth or 240 group, and thus will have previously closed the switches 322 to 326, inclusive, actuating the switch bar 301 and opening the switch 340 so that the circuit to the magnet or solenoid 314 will be broken at this point. But if less than all five of the dogs, and more than one of the dogs on the tracks 52 to 56, inclusive, move past the third or 230 group and the fourth or 240 group of switch bars, the consequent closing of the corresponding switches in the groups 350 to 420 will complete the circuit through the magnet or solenoid 314, which will be energized to withdraw the latch 312 and to permit the spring 308 to actuate the switch bar 302. The actuation of this switch bar will immediately open the switch 341 which will not only save further flow of current through the solenoid or magnet, but also will prevent subsequent actuation of the switch bar 301 if one or more dogs should make a late start in the race and should close all of the still open switches of the 320 to 330 groups at a time after the switch bar 302 had already been actuated.

The purpose of having the circuits controlling the switch bars 301 and 302 pass through two different groups of individual track switch bars instead of through only one group, is so that unscrupulous players of the game will not be able to leave one or more dogs stationary on the track in such position as will help to close the necessary circuits for actuating the bars 301 and 302, and thus get credit, so far as the prizes are concerned, for playing a greater number of dogs than the number for which the fees have actually been paid. Since no dog has any effect upon closing the circuit to the solenoids 313 or 314 until such dog moves past two different individual track switch bars, it follows that a player can gain no advantage by leaving a dog stationary in a position to trip one of such switch bars.

The mechanism for determining which dogs make first, second, and third places in each race will now be described, in order that this may be understood before proceeding to a description of the winner indicating and prize distributing circuits, which necessarily pass through the selecting mechanism. Referring now to Figs. 19 to 23, inclusive, the selecting mechanism comprises a series of individual first place magnets 431 to 436, inclusive, one corresponding to each of the six tracks 51 to 56, inclusive, and a larger first place controlling magnet 438. Mounted adjacent these magnets is a bar 439 of insulating material, pivoted on pivot pins 440 so that it may

- tilt. This bar 439 carries an armature 441 which is attracted when the controlling magnet 438 is energized, and such attraction tilts the bar 439 against the influence of a light spring 442 which normally holds the armature 441 away from the magnet 438.
- Mounted on this bar 439 are six resilient fingers 451 to 456, each in alignment with one of the magnets 431 to 436, respectively. These fingers 451 to 456 are of magnetic material, so that they may be attracted by and act as armatures for their respective magnets, and have a considerable amount of resilience so that one of the fingers may, when attracted by its corresponding magnet, be bent to a considerable degree without causing it to draw away from its magnet.
- Slightly spaced from the ends of the respective magnets 431 to 436 are contact members 461 to 466, inclusive. The resilient fingers 451 to 456 extend down into the spaces between the magnets and the contacts, as shown, and each finger is adapted to contact either with its corresponding magnet or with its corresponding contact piece, and make electrical connection therewith. The pole tips of the magnets form part of the electrical circuits, so that when any of the spring fingers contact with the pole tips or their magnets, the circuits through the windings on those magnets are closed at that point.
- On the first or finish line group of individual track switch bars 211 to 216, inclusive, are switches 481 to 486, respectively, which may be referred to as the switches of the "480" group. Conductors run individually from each of these switches 481 to 486 to the spring fingers 451 to 456, respectively, as indicated in Fig. 36. Each of these fingers is normally held against the pole piece of its respective magnet 431 to 436, completing the circuit to the magnet, which circuit then runs through the winding around the magnet. From the individual magnets the winding circuits all pass around the controlling magnet 438, as indicated in Fig. 21, and also as shown diagrammatically in Fig. 36. Thus the controlling magnet 438 has six separate windings on it, all insulated from each other, which windings may be arranged in overlapping relation to each other, or in separate cylindrical zones around the controlling magnet, but which preferably are arranged in the manner shown in Fig. 21, the six wires from the six individual magnets being arranged side by side to form what might be termed a ribbon or band of wires wrapped spirally around the controlling magnet.
- Now if it be assumed that the circuits are not open at some other place but are all closed except for the open finish line switches of the 480 group, it is seen that the first dog to arrive at the finish line will close his corresponding switch of this group. This will complete the circuit through his individual magnet of the 430 group, because all of the fingers 451 to 456 are in contact with the pole pieces of their respective magnets. As soon as any one of these six circuits is closed, however, the current will flow not only through the individual magnet of the 430 group, but also through the controlling magnet 438. This will cause the controlling magnet to attract the armature 441, and will swing the bar 439 against the influence of the spring 442, swinging all of the other spring fingers 451 to 456 away from the pole pieces of their corresponding magnets of the 430 group, and swinging them into contact with the contact members 461 to 466. The one spring

finger of the 450 group which completed the circuit (that is, the spring finger corresponding to the first place dog) will not swing away from its associated magnet of the 430 group, however, because current will be flowing through this magnet 5 and the attraction of the magnet will be sufficient to maintain the spring finger in contact with the pole tip of the magnet, maintaining the circuit closed at this point, although all of the other spring fingers will be moved away from their magnets, since no current is then flowing through these individual magnets and the magnets do not attract their spring fingers.

In this way, the individual circuit corresponding to the first place or winning dog is selected 15 out of the other circuits and continued through and beyond the control magnet 438, so that it may operate indicating means and paying means. The other circuits corresponding to the other dogs are shunted or side-tracked, as it were, away from 20 the controlling magnet 438, and are connected to the contact members of the 460 group.

The winning dog individual circuits, after leaving the control magnet 438, pass independently to winner indicating means such as the electric 25 lamps 491 to 496, inclusive (Fig. 36) one such lamp corresponding to each dog. Since only one of these circuits can be energized at a time, the others being shunted off as above explained, it is apparent that only the lamp corresponding to 30 the winning dog will be lit. Thus, the lighting of one of the lamps of this 490 group will indicate that the dog running on the track corresponding to its individual one of the lamps is the dog which won first place in the race; that is, the dog which 35 first got to the finish line and tripped his switch bar of the 210 group, closing his individual switch of the 480 group.

The mechanism for selecting the second place dog may be substantially identical with the first 40 place selecting mechanism, corresponding parts being indicated by the same numerals used in the first place mechanism, except that these numerals are in the 500 series instead of the 400 series. Individual circuits, one corresponding to 45 each track, pass from the contact members 461 to 466, inclusive, to corresponding individual spring fingers 551 to 556, inclusive, of the second place dog selecting mechanism, constructed just like the spring fingers 451 to 456, and cooperating 50 similarly with individual magnets 531 to 536, corresponding to the magnets 431 to 436. The control magnet 538 of the second place selecting mechanism operates, like the magnet 438 of the first place selecting mechanism, to swing the 55 spring fingers 551 to 556 away from the pole tips of their magnets 531 to 536, and into contact with contact members 561 to 566, except that, as before, the one spring finger whose corresponding individual magnet is energized will not be swung 60 away from its magnet, but will remain in contact therewith due to the attraction of the magnet. Thus, after the first dog has come in, the circuits corresponding to the other dogs who have not yet 65 reached the finish line will all extend to the spring fingers of the 450 group, through these to the contacts of the 460 group, from these to the spring fingers of the 550 group, and through these to the individual magnets of the 530 group. Then, 70 as soon as the next dog reaches the finish line and closes one of the switches of the 480 group, his individual circuit will be energized, his individual magnet of the 530 group will be energized so as to maintain its individual spring finger of the 550 75

group in contact with this magnet, and the second place control magnet 538 will be energized to draw all of the other spring fingers away from their individual magnets and move them into contact 5 with the contacts of the 560 group. The individual circuit of the second place dog will remain closed through his individual magnet of the 530 group, however, and this circuit, after passing through the winding of the control magnet 538, 10 goes to one of the electric lamps 591 to 596, inclusive, these lamps being the second place dog indicating lamps. Thus, the one of the lamps of the 590 group which lights will indicate which of the dogs make second place in the race.

15 Similarly, the third place selecting mechanism may be constructed the same as the first and second place selecting mechanism, except that the contacts corresponding to the 460 group or the 560 group are not needed in the third place selecting mechanism unless more than three places are to be selected or determined. The parts of the third place selecting mechanism are indicated by the same reference numerals used for the first and second place selectors, except that these numerals are of the 600 series instead of the 400 or 20 500 series.

Individual circuits run from the contacts 561 to 566 of the second place selecting mechanism to the spring fingers 651 to 656 of the third place 30 selecting mechanism. These fingers, as in the other mechanisms, are initially in contact with the pole tips of the magnets 631 to 636, respectively, and the circuits continue through the magnets to the third place control magnet 638 which 35 operates upon the armature 641 to swing the bar 639 to swing all of the spring fingers of the 650 series away from their individual magnets, except the one spring finger in the circuit of the third place dog.

40 The individual circuits from the magnets of the 630 group after passing through the multiple winding of the control magnet 638, go to the third place lights of the 690 group, indicated at 691 to 696, inclusive, one light for each dog track. The 45 light of this group which lights will show which of the dogs made third place in the race.

The selecting mechanism may be continued in a similar manner to indicate the fourth and fifth place dogs, or any other desired number of places 50 if desired, merely by duplicating the mechanism in the form already described. If no places beyond the third place are to be indicated, however, the contacts corresponding to the 460 group of the first place selector and the 560 group of the 55 second place selector can be omitted in the third place selector and when the spring fingers of the 590 group are pulled away from the individual magnets of the 630 group, these spring fingers will not make new contacts but will simply form 60 dead ends for the other circuits except those of the first, second, and third place dogs.

Separate prize or reward paying or delivering 65 mechanisms are associated with each dog track, so that there can be no argument between the various players of the game as to which one is entitled to the prize or reward. Thus, when the game includes six tracks around which the movable playing pieces run, there are preferably six 70 separate paying or delivering mechanisms, each capable of delivering the proper coins, tokens, or other prizes into a chute 702 (Fig. 33) having a spout 703 (Fig. 1) in the side of the casing and adjacent the crank 61 controlling the dog or other playing piece with respect to which the prize or 75 reward is to be delivered. Each delivering mech-

anism may be of any suitable known form of electrically operated or electrically controlled delivering mechanism. For instance, each delivering mechanism may include a cylindrical holder 705 for holding a stack of coins or tokens of one denomination or kind, another cylindrical holder 706 for holding a stack of coins or tokens of a different denomination or kind and other similar holders 707 and 708 for holding other stacks of still different coins or tokens. Merely as an example, the holders 705 may hold half dollars, the 10 holders 706 may hold dimes, the holders 707 may hold nickels, and the holders 708 may hold pennies. Of course, the denominations may be varied at will, by substituting holders of the proper 15 size to receive the desired denominations, and instead of using actual coins in the holders, some or all of the holders may contain tokens redeemable by the proprietor of the game either in 20 money or in merchandise.

The bottom coin or token from each holder 25 may be ejected therefrom by movement of a suitable apertured slide 709, the slide being actuated, for example, by means of a solenoid. When the solenoid is energized, the slide is moved and the 30 coin or token is withdrawn from the bottom of the stack and allowed to drop through an opening, as indicated by dotted lines in Fig. 34, so that it falls into the chute 702 and slides by gravity to the spout 703 where it may be collected by the 35 player who is entitled to it.

The slides of the several holders 705 may be 40 actuated by solenoids of the 710 group (Fig. 33) comprising the six solenoids 711 to 716, inclusive (Fig. 36), one corresponding to each of the six 45 dog tracks 51 to 56. Similarly, the ejector slides for the holders 706 may be operated by the solenoids of the 720 group, these being the solenoids 721 to 726, inclusive. The slides for the holders 707 are actuated by the 730 solenoids numbered 40 from 731 to 736, while the slides for the 708 holders are actuated by the 740 solenoids numbered from 741 to 746, all as shown in Fig. 36.

The first, second, and third place circuits, after 50 passing the indicating lights of the 490, 590, and 690 groups, pass to the solenoids of the 720, 730 and 740 groups, as shown in Fig. 36, but in so doing they go through the control switches mounted on the switch bars 301 and 302, since 55 these switches are operated in accordance with the number of dogs running the race and determine the number of prizes or rewards to be delivered and the amounts thereof. The circuits to the reward delivering solenoids of the 720, 730, and 740 groups are all open until one or the other 60 of the switch bars 301 and 302 is actuated, as plainly seen from Fig. 36.

If all six dogs run in the race, then the switch bar 301 is actuated but the bar 302 is not actuated as above explained. The actuation of the bar 301 65 (which takes place, however, long before any of the dogs get around to the finish line) completes the circuits to the solenoids which are otherwise broken at this point, and by tracing the circuits in Fig. 36, it will be seen that whichever dog comes in first, lighting one of the lights of the 490 series, will energize a circuit passing through the switches on the bar 301 and to one of the solenoids of the 720 group, corresponding to the 70 particular dog which won the race. Thus the player who played this winning dog will receive in his individual spout 703, whatever coin or token is delivered by the solenoids of the 720 group, this being a dime in the illustrative example above 75 given.

By tracing the circuits it will also be seen that whichever dog reaches the finish line in second place and lights one of the lights of the 590 series, will energize a circuit going to his individual solenoid of the 730 group, this delivering to the player of that dog the coin or token which is intended to be delivered to the second place dog. This is a nickel in the illustrative example above given. Similarly, whichever dog makes third place and lights one of the lights of the 690 group will energize a circuit passing to his individual one of the solenoids of the 740 group, thus energizing this solenoid and delivering to the player of this dog the intended reward, such as a penny in the illustrative example above given.

If, however, the entrance fees or playing fees for all six dogs have not been paid and the dogs at least on tracks 52 to 56 have not passed the switches of the 320 and 330 groups, then the switch bar 301 will not have been actuated, and the above mentioned circuits will all be broken at this point. But if any two of the dogs on tracks 52 to 56 are running (thus making at least three dogs in all, including the dog on main or control track 51) then, as above explained, the switch bar 302 will be actuated and the switches connected to this bar, which are shown to be open in Fig. 36, will all be closed, the switches on this bar shown in Fig. 36 to be closed also being opened at the same time. If, now, the circuits from the first place lights of the 490 group be again followed, it will be seen that these circuits lead through the switches on the bar 302 to the solenoids of the 730 group. Hence the player of the winning dog, when more than two but less than all six of the dogs run in the race, will receive a coin or token ejected by his individual solenoid of the 730 group, this being a nickel coin in the illustrative embodiment above given.

When less than all six dogs run, no prizes or rewards are given to the players of any dog except the first place dog according to the present illustrative example. It is desired, however, to have the proper lights of the 590 group and 690 group show which dogs make second and third place. Hence, it is necessary to provide, in connection with the switch bar 302, some means for completing the circuits from the second and third place lights of the 590 and 690 groups so that electric current can flow through these circuits and light the proper light but without actuating any of the reward delivering solenoids. This is provided for by including on the switch bar 302 switches which complete the second and third place dog circuits to a conductor 750, in which is interposed a resistance 751 approximately equal to the resistance of each of the solenoids of the 720, 730 and 740 groups. The purpose of this is to make the resistance of all these circuits approximately equal so that the second and third place lights will not light more brightly when less than all six dogs run, than the first place lights. This circuit, like all of the other place indicating and reward delivering circuits, is shown in Fig. 36 as being grounded at its remote end; that is, as being a circuit which returns to the source of current through the metallic frame of the machine, or through a common or universal bus bar, although complete two-wire circuits can be used in each instance if preferred.

In case less than three dogs run the race, neither of the switch bars 301 and 302 will be actuated. While it is desired not to deliver any prize or rewards when less than three dogs run the race, yet

it is desired to have the place indicating lights operate to show which dog is the winner. Provision must, therefore, be made for completing the circuits from the first place lights of the 490 group in order to permit current to flow through these lights, even when neither of the switch bars 301 and 302 is actuated. This provision is made as indicated in Fig. 36 by completing the circuits from the lights of the 490 group to switches mounted on the bar 302, and normally closed when this bar is not actuated, these switches being opened by the actuation of the switch bar. Beyond these switches, the individual track circuits of the winning group are all joined to a common wire 755, which passes through a switch 756 on the switch bar 301 and then leads to the wire 750 above mentioned.

Hence, when neither of the switch bars 301 and 302 has been actuated the circuits of the first place lights of the 490 group will all be completed to the wire 755, then through the switch 756 to the wire 750, and through the resistance 751 to ground. Whichever dog makes first place will then cause the lighting of its respective light of the 490 group. If the switch bar 301 has been actuated, however, by reason of all six dogs running the race, then this lighting circuit will be broken through the switch 756 which is closed when the bar 301 is not actuated and opened when the bar 301 is actuated. Or if the bar 302 is actuated, the circuits from the first place lights of the 490 group to the wire 755 will be broken by the opening of the switches on the bar 302 but these circuits will simply be transferred to the wires leading to the solenoids of the 730 group, so that the proper light of the 490 group will light and the proper solenoid will be energized.

It is desirable to provide mechanism for turning off all of the circuits after the lapse of a predetermined time, so that the lights will not stay lit indefinitely and will not waste electric current. To this end a time switch is preferably provided somewhere in the circuit, to turn off all of the place indicating light circuits at a given length of time after the game starts. This length of time is a time amply sufficient to allow for completion of the game even by slow and unskillful players. It may be, for example, one or two minutes in a small game board, or perhaps five minutes in a larger game board where the tracks are longer and a greater time is required to run the dogs around the tracks.

The time switch may comprise clockwork of any conventional kind within a casing 760 (Figs. 24, 25 and 36), the clockwork tending to turn a vertical shaft 761 which extends up through the top of the playing board 41 and is there provided with a suitable needle 762 cooperating with graduations on the board to show the players at any instant how much time is left for them to complete the game before the electric circuits will be broken. The graduations illustrated in Fig. 1 run from zero to 60 and are intended to refer to seconds, the players being allowed a period of one minute to complete the game.

A gear 765 (Figs. 24 to 27) is loosely mounted for rotation on the shaft 761, and has a pin 766 in such position that when the gear is rotated the pin will engage with another pin 767 fixed to a disk 768 which is pinned or otherwise non-rotatably secured to the shaft 761. A rack 770, held in meshing engagement with the gear 765 by a bracket 771, is actuated by the coin controlled mechanism of the main or control track 75

51, as indicated in Figs. 7 and 8. The inward push of the coin slide of this control track shoves the rack 770 inwardly (or upwardly when viewed as in Figs. 7 and 8) from the position of Figs. 5 5 and 26 to the position of Figs. 8 and 27, rotating the gear 765 until the pin 766 comes into contact with the pin 767, picks up this pin, and carries it around with it, rotating the disk 768 and the shaft 761 to rewind the spring of the 10 clockwork 760. At the completion of the inward movement of the rack, a latch 775 drops into a hole 776 in the disk 768, preventing unwinding or running down of the clockwork until the latch is released. This latch 775 may be 15 formed as an extension of the bar 184 (Fig. 9) which is actuated by movement of the rabbit 101 past the kennel. As the rabbit passes the kennel and actuates the link 192 to depress one end of the bar 184 to open the kennel door, this 20 raises the opposite end of the bar 184, lifts the latch 775 out of the hole 776 and releases the clockwork so that it begins to run down.

At some suitable point in the main circuit passing through the switches of the 480 group 25 to the place indicating lights is a switch indicated in Figs. 24 and 25 in a somewhat diagrammatic manner as comprising a contact member 780 for completing the circuit across spaced contacts 781. A spring 782 normally holds the 30 switch closed. An arm 783 operatively connected to the contact piece 780 extends upwardly to a position just beneath the disk 768 and in the path of travel of a cam 785 on the disk. At the 35 end of the desired time interval after release of the latch 775 which sets the clockwork in operation, the cam 785 reaches the arm 783 and moves this arm from the position shown in Figs. 25 and 27 to the position shown in Figs. 24 and 26, thus moving the contact piece 780 away from the member 781 and opening the main switch. 40 Slight additional rotation of the shaft 761 and disk 768 brings an abutment shoulder 786 (Fig. 28) against the side of the arm 783 and thus the arm acts as a stop to prevent further rotation of the clock mechanism. The clock mechanism then remains in this run down position, with the main switch open, until the coin controlled mechanism associated with the main track 51 is again actuated, moving the rack 770 inwardly and rewinding the clock, which removes 45 the cam 785 from the arm 783 and allows the spring 782 to close the main switch.

At the same time that the clock is rewound and the main switch is closed, all of the other 55 switches which have been actuated are reset to their normal initial positions. This may conveniently be done by providing, on the rack 770, a cam 790 (Figs. 7 and 8) which, when the rack 60 bar is moved inwardly, operates against a roller 791 mounted, as best shown in Figs. 11 to 13, on a restoring plate 792 which is mounted for movement in a direction lengthwise of the dog tracks, being swung on pivoted hangers 793. This restoring plate is normally in the position shown 65 in Figs. 11 and 13, where downwardly extending portions of the various switch bars of the 210, 220, 230, and 240 groups and switch bars 301 and 302 extend down into slots 795 in the plate 792. A spring 796 acting on one of the hanger 70 links 793 normally holds the restoring plate at the left hand end of its limit of motion when viewed as in Figs. 11 to 13.

In this position, the slots 795 are sufficiently long to permit leftward movement of the lower 75 ends of any of the switch bars of the 210, 220,

230 and 240 groups, or of the switch bars 301 and 302. When the rack 770 is moved inwardly, however, the cam 790 operates against the roller 791 to shift the plate 792 rightwardly from the position shown in Figs. 11 and 13 to the position 5 shown in Fig. 12, where the left hand ends of all of the slots 795 come into contact with the downward projections on all of the switch bars and restore these switch bars in a rightward direction to their initial positions where they are 10 caught and held by their respective latches. Then when the coin controlled mechanism associated with the main track 51 is released, the rack 770 moves outwardly again and the spring 15 796 moves the restoring plate 792 leftwardly again to its initial position shown in Figs. 11 and 13 but the switch bars stay in their reset position until their respective latches are actuated by the travel of the dogs.

Referring again to Fig. 36, the main source 20 of current for operating the place indicating lights and the reward delivering mechanism is indicated diagrammatically by the battery 800. One side of this battery is grounded, to connect through the metallic frame of the machine with 25 the grounded ends of the various circuits above mentioned, and the other side of the battery is connected through the time switch 780 (here shown diagrammatically as an arcuate conductor contacting during a part of the rotation of 30 the shaft 761 with the contact 781) to each of the individual finish line switches of the 480 group.

At the completion of the predetermined time 35 interval after the game is started by the running of the rabbit past the kennel to open the kennel door and to trip the time clock, the switch 780, 781 will be opened to open all of the circuits through the place indicating lights and save further flow of current. Then when the clock is 40 rewound by operating the coin controlled mechanism associated with the main control track 51, the main switch 780, 781 will again be closed, but concomitantly therewith the switches of the 480 group will all be opened by operation of the 45 restoring plate 792, so that the circuits to the place indicating lights will be opened at these switches until the completion of the race and the arrival of the dogs at the finish line switches of the 480 group. 50

To make the game still more interesting, a special prize or reward may be given to those players whose dogs complete the race in less than a certain predetermined time, irrespective of the number of dogs which run in the race 55 and irrespective of the order in which they arrive at the finish line. In other words, this reward or prize may be given purely as the result of a race against time. The time will, of course, be set so short that only a very skilful player 60 can get his dog around the track within this time limit and win the special prize or reward. It may be, for example, fifteen seconds, or whatever other time is selected as a reasonable interval by the designer of the apparatus. 65

The circuit from the main battery 800 to the special prize or reward delivering mechanism goes through a special time switch indicated diagrammatically in Fig. 36, and shown structurally in Figs. 24, 25, 29, and 30. The shaft 761 of the 70 clock mechanism carries a cylinder 802 of insulating material, containing a metallic conducting segment 803. Contact members 804 and 805, respectively, contact with the end and side faces, respectively, of the insulating block 802 75

or the contacting block 803, as the case may be, depending upon the rotative position of the shaft 161. When the clock mechanism is rewound and set to its initial position shown in Figs. 25 and 5 30, the contacts 804 and 805 contact with the metallic block 803 at one edge thereof, and the block completes the circuit between the contacts. When the race starts and the clockwork begins to 10 run down, the metallic block 803 continues to be in contact with the members 804 and 805 for the selected limited time, such as fifteen seconds, and at the end of this time the trailing edge of the block 803 moves out from under the contacts 804 and 805, breaking the connection between 15 them and opening all of the special prize circuits at this point.

From the switch 803, the circuit goes to each of a series of individual track switches 811 to 816, inclusive, (Fig. 36) which may be referred to as 20 the 810 group of switches, and which are mounted on the switch bars 211 to 216, inclusive, of the first or finish line group of switch bars. From each of the switches of this 810 group, the individual circuit of that individual track goes to 25 another switch 821 to 826, respectively, constituting the switches of the 820 group, these being mounted on the second or 220 group of switch bars 221 to 226, inclusive. From these switches of the 30 820 group, the circuit of each individual track goes to the proper individual solenoid of the 710 group. At approximately the beginning of each race, each dog that runs in the race will close his individual switch of the 820 group. At the 35 end of the race, when he reaches the finish line, he will close his individual switch of the 810 group. If he has gotten around to the finish line while the switch 803 is still closed (that is, within the predetermined selected short time interval) then the closing of the switch of the 810 40 group will complete the circuit to the appropriate one of the solenoids of the 710 group, to deliver the special prize or reward to the player of this particular dog that was successful in getting around the track within the short time limit. In 45 the illustrative embodiment above given, this special prize or reward is a half dollar, but it may, of course, be a coin of any other denomination, or a token redeemable in money or in merchandise.

It is seen that the circuits passing to the special prize solenoids of the 710 group are independent of the number of dogs that run and independent of which dog comes in first, so that the delivery of these special prizes depends solely upon whether or not any particular dog gets 55 around the track within the short special time limit applicable to these special prizes.

If desired, the circuits through the finish line switches and to the winner selecting mechanism may pass from the main switch 780, 781 to individual track switches placed upon the switch bars of the second group or 220 group, and then through these switches and individually to the respective track switches of the 480 group, on the finish line switch bars of the 210 group, each individual track circuit thus being controlled by two switches mounted on two different switch bars, in a manner similar to the control of the circuits through the switches of the 810 group and the switches of the 820 group to the solenoids 65 of the 710 group. The advantage of running each circuit through two separate switches in series is that players of the game cannot unfairly obtain prizes or rewards by leaving one or more dogs in stationary position to trip the finish line 70 switches on the 210 group of bars and to make 75

these switches close without actually running the dogs around the track.

The various place indicating lights of the 490, 590 and 690 groups may conveniently be placed on the playing board in the central space within 5 the rabbit track 57, as indicated in Fig. 1.

While one embodiment of the invention has been disclosed, it is to be understood that the inventive idea may be carried out in a number of ways. This application is, therefore, not to be limited to the precise details described, but is intended to cover all variations and modifications thereof falling within the spirit of the invention or the scope of the appended claims.

I claim:

1. A game comprising a track, an upright post, means for moving said post along said track, a figure pivotally mounted on said post at a point forwardly of the center of gravity of said figure so that gravity tends to turn the rear end of said figure downwardly, cooperating abutment means on said post and said figure to limit downward turning of said rear end to hold said rear end normally elevated above said track, said figure having a front depending portion and a rear depending portion, inclined cam means adjacent said track and out of alinement with said front portion when said figure is in said position but in alinement with said rear portion in said position to engage said rear depending portion as 30 said figure passes said cam means to lift said rear depending portion and cause lowering of said front depending portion, and an obstruction adjacent said track beyond said cam means and having a rear wall extending in a generally upward direction sufficiently far to contact with the lowered front depending portion of said figure and stop forward movement of said figure unless said front depending portion has been restored to an elevated position before it reaches said obstruction.

2. A game comprising a track, a continuous flexible element extending along said track, means for driving said element, a supporting member mounted on and moving with said element, a figure mounted on said supporting member to move therewith along said track, said figure being pivoted to said supporting member for oscillating movement relatively thereto about a pivot located forwardly of the center of gravity of the 50 figure so that gravity tends to lower the rear portion of said figure, cooperating abutment means on said supporting member and said figure for preventing downward movement of said rear portion of said figure beyond a predetermined elevation, a rear depending portion and a front depending portion on said figure, inclined cam means adjacent said track to engage said rear depending portion as said figure passes said cam means and to lift said rear depending portion 60 against the action of gravity to cause lowering of said front depending portion, and an obstruction adjacent said track beyond said cam means to contact with the lowered front depending portion of said figure unless gravity has meanwhile 65 restored said front depending portion to an elevated position before it reaches said obstruction.

3. A game comprising a track, means movable along said track, a member movably mounted on said means to move bodily therewith along said track and also to move relatively to said movable means, said member having a normal position relatively to said movable means and having a forwardly extending projection near its front end, means adjacent said track for shifting said 75

member substantially from its said normal position as said member passes said shifting means, to move said projection downwardly and obstructing means beyond said shifting means and 5 extending obliquely upwardly and rearwardly for contacting with said projection on said member when said projection is in its downward position to arrest forward motion of said member.

4. A game comprising a track, supporting 10 means including an upwardly extending member, means for moving said supporting means along said track, an animal figure having a cavity in its under side, said member extending upwardly into said cavity, a pivot pin extending through said 15 member and said figure to connect them pivotally to each other at a point horizontally offset from the center of gravity of said figure, so that gravity tends to rotate said figure in one direction about said pivot, cooperating parts on said member and 20 said figure for contact with each other to limit rotation in said direction to maintain the heavier end of said figure in normally elevated position, and hurdle means adjacent said track to contact with said heavier end of figure to rotate it in the 25 opposite direction about said pivot, when said figure is moved along said track past said hurdle means.

5. The combination with a plurality of tracks, 30 of a plurality of playing pieces, one movable along each track, means for moving each playing piece along its track independently of movement of the other playing pieces along their tracks, means for delivering a variable number of rewards of a plurality of kinds, and means controlled by the number of playing pieces moving along said tracks for determining the number and 35 kind of rewards to be delivered.

6. A game including a plurality of tracks, a plurality of playing pieces, one movable along 40 each track, and also including means for moving each playing piece along its track independently of movement of the other playing pieces along their tracks, said game being characterized by means for delivering a variable number of rewards of a plurality of kinds, and further characterized by means controlled by the number of 45 playing pieces moving along said tracks for determining the number and kind of rewards to be delivered.

7. The combination with a plurality of tracks, 50 of a plurality of playing pieces, one movable along each track, means for moving each playing piece along its track independently of movement of the other playing pieces along their tracks, means for delivering a variable number of rewards of a plurality of kinds, means controlled 55 by the number of playing pieces moving along said tracks for determining the number and kind of rewards to be delivered, and means controlled by the order of arrival of the playing pieces at a 60 predetermined line for determining the distribution of the rewards to be delivered.

8. The combination with a plurality of tracks, 65 of a plurality of playing pieces, one movable along each track, manually controlled means for moving each playing piece along its track independently of movement of the other playing pieces along their tracks, a plurality of reward delivering mechanisms, one associated with each track, 70 timing mechanism, and means controlled at least in part by movement of said playing pieces along their tracks and by said timing mechanism for operating said delivering mechanisms.

9. The combination with a plurality of tracks, 75 of a plurality of playing pieces, one movable along

each track, means for moving each playing piece along its track independently of movement of the other playing pieces along their tracks, a plurality of reward delivering mechanisms, one associated with each track, each of said delivering 5 mechanisms including means for delivering a plurality of different kinds of rewards, means controlled by the number of playing pieces moving along their respective tracks for determining the number of delivering mechanisms which may 10 be operated, and means controlled by the order of arrival of the respective playing pieces at a predetermined line for determining which of said delivering mechanisms shall be operated.

10. The combination with a plurality of tracks, 15 of a plurality of playing pieces, one movable along each track, means for moving each playing piece along its track independently of movement of the other playing pieces along their tracks, a plurality of reward delivering mechanisms, one as- 20 sociated with each track, each of said delivering mechanisms including means for delivering a plurality of different kinds of rewards, means controlled by the number of playing pieces moving along their respective tracks for determining the 25 number of delivering mechanisms which may be operated and the kinds of rewards which may be delivered thereby, and means controlled by the order of arrival of the respective playing pieces at a predetermined line for determining which of 30 said delivering mechanisms shall deliver which kinds of rewards.

11. A construction according to claim 9, further including timing mechanism for rendering at least parts of said delivering mechanisms in- 35 operative after the lapse of a predetermined time.

12. A construction according to claim 9, further including timing mechanism for rendering parts of said delivering mechanisms inoperative after lapse of one time interval and for rendering 40 other parts of said delivering mechanisms inoperative after lapse of a different time interval.

13. A game including a series of playing pieces movable toward a finish line and adapted to arrive at said line at different times, characterized by a 45 series of first place circuits, one corresponding to each playing piece, a series of second place circuits, one corresponding to each playing piece, a series of finish line switches, one corresponding to each playing piece, said switches being several- 50 ly operated by the arrival of their respective playing pieces at said finish line, means initially connecting said switches to said first place circuits, and means operable upon the operation of the first of said switches for connecting all the other 55 switches to said second place circuits and disconnecting them from said first place circuits.

14. A game according to claim 13, further characterized by indicating means in each of said first place circuits and other indicating means 60 in each of said second place circuits, so that operation of said indicating means will indicate which of said playing pieces arrives first at said finish line and which of said playing pieces arrives second at said finish line.

15. The combination with a plurality of tracks, 65 of a plurality of playing pieces, one movable along each track, means for moving each playing piece along its track independently of movement of other playing pieces along their tracks, a plurality of reward delivering mechanisms, one associated with each track and each capable of 70 delivering a plurality of kinds of rewards, electric circuit means associated with each track, said circuit means including switch means operated 75

- by arrival of a playing piece at a predetermined finish line, and magnetic means controlled at least in part by said electric circuit means for delivering a reward of one kind from that mechanism associated with the playing piece first reaching a predetermined finish line and also a reward of a different kind from that mechanism associated with the playing piece next reaching said finish line.
10. 16. The combination with a plurality of tracks, of a plurality of playing pieces, one movable along each track, means for moving each playing piece along its track independently of movement of other playing pieces along their tracks, a plurality of reward delivering mechanisms, one associated with each track, each of said mechanisms being capable of delivering a plurality of kinds of rewards, and means controlled at least in part by movement of said playing pieces along their tracks for delivering one kind of reward from that mechanism associated with the playing piece first reaching a predetermined finish line and a different kind of reward from that mechanism associated with the playing piece next reaching said finish line.
15. 17. The combination with a plurality of tracks, of a plurality of playing pieces, one movable along each track, means for moving each playing piece along its track independently of movement of other playing pieces along their tracks, a plurality of reward delivering mechanisms, one associated with each track, timing means, and means controlled partly by said timing means and partly by movement of said playing pieces along their tracks for delivering a reward from the delivering mechanism associated with each playing piece which completes a predetermined movement along its track within a predetermined time interval.
20. 18. A game comprising a plurality of tracks arranged approximately concentrically with respect to each other, each track forming a closed path of travel, a plurality of endless flexible members, one extending around each track, a figure piece connected to each endless member to be driven thereby around its track when its connected endless member is moved, a plurality of manually operable cranks, one for each track, a plurality of first rotary friction disks, one driven by each of said cranks, a plurality of second rotary friction disks respectively rotatable about axes substantially perpendicular to the respective rotary axes of the first friction disks, one of said second disks contacting with and being driven by each of said first rotary friction disks, centrifugal governor means for shifting one of the rotary friction disks of each pair of contacting friction disks closer to or farther from the rotary axis of the other one thereof to vary the driving ratio between them, and means operatively connecting each of said second rotary friction disks to one of said flexible members to drive the flexible members from said cranks.
25. 19. A racing game comprising a plurality of endless tracks, a plurality of playing pieces, one associated with each track, separate manually operable means for moving each playing piece around its track to a predetermined finish line, electrically operated indicating means for indicating which of said pieces first reaches said finish line, said indicating means including an electric switch operated substantially when the first playing piece reaches said line, movable barrier means beyond said finish line, said barrier means having a normal position obstructing movement of said playing pieces beyond said barrier means, and a shiftable resetting member operable independently of movement of said playing pieces and operatively connected both to said barrier means and to said switch for moving said barrier means to non-obstructing position and for concomitantly resetting said electric switch to non-operated position when said resetting member is shifted.
30. 20. A racing game comprising a plurality of endless tracks having a starting line and a finish line spaced from each other, a plurality of playing pieces, one associated with each track, means for moving each playing piece around its track from said starting line to said finish line, movable barrier means having a normal position obstructing movement of said playing pieces from said finish line to said starting line, indicating means including a separate electric switch individual to and associated with each track adjacent said starting line to be operated by movement of its associated playing piece approximately when said playing piece starts to move along said track from said starting line and a separate electric switch individual to and associated with each track adjacent said finish line, each of said finish line switches being separately operable by movement of its respective associated playing piece approximately when said playing piece arrives at said finish line, and means operable independently of movement of said playing pieces and operatively connected both to said barrier means and to said switches for moving said barrier means to non-obstructing position to permit movement of the playing pieces from said finish line to said starting line and for concomitantly restoring all of said switches to non-operated position ready for operation in another race.
35. 21. A racing game comprising a plurality of endless tracks having a finish line and a starting line spaced forwardly beyond the finish line in the direction of racing movement, a plurality of playing pieces, one associated with each track, means for moving each playing piece around its track from said starting line to said finish line, movable barrier means having a normal position obstructing movement of said playing pieces from said finish line forwardly to said starting line, means for moving said barrier means to non-obstructing position so that said playing pieces may be moved forwardly to said starting line ready to run another race, other barrier means for holding all of said playing pieces substantially at said starting line when they have been moved forwardly thereto, and means for releasing said other barrier means so that said playing pieces may move forwardly from said starting line to run a race.
40. 22. A racing game comprising a plurality of endless tracks having a finish line, a plurality of playing pieces, one associated with each track for movement therealong, manually driven rotary means individual to each track for moving its associated playing piece along its associated track, means associated with each rotary means and operated upon arrival of its associated playing piece at a predetermined position for disabling only its associated rotary means to render said rotary means ineffective to move its associated playing piece without thereby disabling other rotary means from driving their respective playing pieces, said disabling means including an electric switch associated with each track adjacent said finish line and in position to be operated by its associated playing piece as the playing

piece arrives approximately at said finish line, such operation of said switch being effective to cause disabling of its associated rotary means, and means individual to each of said rotary means for reestablishing driving relationship between such rotary means and its associated playing piece only, without thereby establishing a driving relationship between other rotary means and their respective playing pieces.

23. A game including a series of playing pieces movable toward a finish line and adapted to arrive at said line at different times, characterized by a series of first place circuits, one corresponding to each playing piece, a series of second place circuits, one corresponding to each playing piece, a series of finish line switches, one corresponding to each playing piece, said switches being severally operated by the arrival of their respective playing pieces at said finish line, means initially connecting said switches to said first place circuits, reward delivering means operated by said first place circuits, and means operable upon the operation of the first of said switches for connecting all the other switches to said second place circuits and disconnecting them from said first place circuits.

24. A game comprising a plurality of playing pieces mounted for movement toward a predetermined finish line, means for moving said playing pieces toward said line, electrically operated means for delivering a reward with respect to the playing piece first to reach said line, other electrically operated means for delivering a reward with respect to that playing piece second to reach said line, electric circuit means leading to said first reward delivering mechanism to operate the same, other electric circuit means leading to said second reward delivering mechanism to operate the same, a plurality of electric circuits, one corresponding to each playing piece, each of said plurality of circuits containing switch means operated by the arrival of its respective playing piece substantially at said finish line, means for initially connecting all of said plurality of circuits to said electric circuit means leading to the first reward delivering mechanism, and means operated by the arrival of the first playing piece substantially at said finish line for disconnecting said circuits of the remaining playing pieces from said circuit means leading to the first reward delivering mechanism and connecting them to said circuit means leading to said second reward delivering mechanism.

25. A game comprising a plurality of playing pieces mounted for movement, means for moving said playing pieces, a plurality of first electric circuits, one corresponding to each playing piece, each of said circuits including switch means operated upon arrival of its respective playing piece at a predetermined point to cause flow of current through its corresponding circuit, a double throw switch connected to each of said first circuits, a plurality of second electric circuits, one operatively connected to each of said double throw switches to be connected therethrough to its corresponding first circuit when said double throw switch is in one position, a plurality of third electric circuits, one operatively connected to each of said double throw switches to be connected therethrough to its corresponding first circuit when said double throw switch is in its other position, master magnetic means interposed in all of said second circuits to be energized by current flowing through any one of said second circuits, means operatively connecting said master magnetic

means to all of said double throw switches in all of said circuits to tend, when said master magnetic means is energized, to throw all of said double throw switches from second circuit connecting position to third circuit connecting position, individual magnetic means interposed in each of said second circuits to be energized by flow of current through its associated second circuit, and means operatively connecting each of said individual magnetic means to its associated double throw switch to hold said double throw switch in second circuit connecting position when said individual magnetic means is energized, notwithstanding the tendency of said master magnetic means to move all of said double throw switches from second circuit connecting position to third circuit connecting position.

26. A game comprising a plurality of playing pieces mounted for movement, means for moving said playing pieces, a plurality of first electric circuits, one corresponding to each playing piece, each of said circuits including switch means operated upon arrival of its respective playing piece at a predetermined point to cause flow of current through its corresponding circuit, a double throw switch connected to each of said first circuits, a plurality of second electric circuits, one operatively connected to each of said double throw switches to be connected therethrough to its corresponding first circuit when said double throw switch is in one position, a plurality of third electric circuits, one operatively connected to each of said double throw switches to be connected therethrough to its corresponding first circuit when said double throw switch is in its other position, electromagnetic means effective upon flow of current through any one of said second circuits to tend to throw all of said double throw switches from second circuit connecting position to third circuit connecting position, individual magnetic means interposed in each of said second circuits to be energized by flow of current through its associated second circuit, and means operatively connecting each of said individual magnetic means to its associated double throw switch to hold said double throw switch in second circuit connecting position when said individual magnetic means is energized, notwithstanding the tendency of said first mentioned electromagnetic means to move all of said double throw switches from second circuit connecting position to third circuit connecting position.

27. A game including a series of playing pieces movable toward a finish line, a series of finish line circuits, one for each playing piece, a series of finish line switches, one in each of said finish line circuits, each of said switches being operated by arrival of its respective playing piece at the finish line, a series of first place circuits, one for each playing piece, a series of second place circuits, one for each playing piece, and switch means initially connecting all of said finish line circuits to said first place circuits until any one of said finish line switches is operated and thereafter connecting the remainder of said finish line circuits to said second place circuits while keeping the one finish line circuit in which said switch was operated connected to its respective first place circuit.

28. A game including a series of playing pieces movable toward a finish line, a series of finish line circuits, one for each playing piece, a series of finish line switches, one in each of said finish line circuits, each of said switches being operated by arrival of its respective playing piece at the

finish line, a series of first place circuits, one for each playing piece, a series of second place circuits, one for each playing piece, a series of double throw switches initially connecting each of said finish line circuits to one of said first place circuits and shiftable to connect each of said finish line circuits to one of said second place circuits,

and electric means operated by flow of current upon closing a finish line switch in any one of said finish line circuits for throwing said double throw switches to connect all of the remaining finish line circuits to their respective second place circuits.
